Specification for Design.

Patented July 7, 1914.

Application filed February 7, 1914. Serial No. 817,358. Term of patent 3½ years.

To all whom it may concern:

Be it known that I, HARRY NORTHWOOD, a citizen of the United States of America, residing at Wheeling, in the county of Ohio and State of West Virginia, have invented a new, original, and ornamental Design for a Spoon-Holder or Similar Article, of which the following is a specification, reference being had to the accompanying drawings, in which—

holder embodying my new design. Fig. 2 is a front elevation of the same; and Fig. 3 is a section taken on the line 3—3, Fig. 1.

I claim:

The ornamental design for a spoon holder or similar article as shown.

HARRY NORTHWOOD.
